UNITED STATES PATENT OFFICE

102,099

DESIGN FOR A CHAIR

Abraham S. Wexelblatt, Philadelphia, Pa., assignor to Bunting Glider Company, Philadelphia, Pa., a corporation of Pennsylvania

Application October 26, 1936, Serial No. 65,511

Term of patent 7 years

To all whom it may concern:

Be it known that I, Abraham S. Wexelblatt, a citizen of the United States and a resident of Philadelphia, county of Philadelphia, State of Pennsylvania, have invented a new, original, and ornamental Design for a Chair, of which the following is a specification, reference being had to the accompanying drawing, forming a part thereof, wherein:—

I claim:

The ornamental design for a chair as shown.

ABRAHAM S. WEXELBLATT.
